United States Patent Office

Des. 233,859
Patented Dec. 3, 1974

233,859

DRAWER

Charles R. Tyke, Lexington, Ohio and William C. Anderson, Grand Rapids, Mich., assignors to Westinghouse Electric Corporation

Filed Apr. 3, 1973, Ser. No. 347,512

Term of patent 14 years

Int. Cl. D15—07; D6—06
U.S. Cl. D67—3 B

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view, with portions thereof broken away, of a drawer illustrating our new design;
 FIG. 2 is a top plan view thereof;
 FIG. 3 is a front elevational view thereof;
 FIG. 4 is a side elevational view thereof;
 FIG. 5 is a bottom plan view thereof;
 FIG. 6 is a rear elevational view thereof;
 FIG. 7 is a front elevational view of a drawer showing a deeper modified form of our new design;
 FIG. 8 is a right side elevational view thereof;
 FIG. 9 is a rear elevational view;
 FIG. 10 is a front elevational view of a drawer showing a shallower modified form of our new design;
 FIG. 11 is a right side elevational view thereof; and
 FIG. 12 is a rear elevational view.

We claim:
 The ornamental design for a drawer, substantially as shown and described.
